UNITED STATES PATENT OFFICE.

WILLIAM S. LANEY, OF LITHOPOLIS, OHIO.

PUMP.

SPECIFICATION forming part of Letters Patent No. 242,140, dated May 31, 1881.
Application filed February 2, 1881. (No model.)

To all whom it may concern:

Be it known that I, WILLIAM S. LANEY, a citizen of the United States, residing at Lithopolis, in the county of Fairfield and State of Ohio, have invented certain new and useful Improvements in Pumps; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to double-lifting pumps; and it consists in the construction and arrangement of the several parts hereinafter described, and pointed out in the claims.

In the drawings, Figure 1 is a side elevation, and Fig. 2 is a vertical section, of a pump constructed according to my invention.

a' are two outer or stand pipes, and a² is an intermediate air-pipe placed between the stand-pipes, as shown. The lower ends of these three pipes are connected together by a horizontal confluent tube or pipe, a³.

a⁴ is a supporting-tube made of such length that its lower end will reach to and stand on the bottom of the well, or on a base specially provided for it. It is connected so that its bore 30 is in direct line with the bore of one of the stand-pipes, so that the piston placed in it can be operated by a rod carried up through stand-pipe above it.

The upper end of the intermediate air-pipe, 35 a², is closed tight, and serves as a fulcrum to which the handle b is pivoted. The upper ends of the stand-pipes a' are closed by caps a⁵, having vertical holes, through which the piston-rods c c' pass downward into the said pipes.

40 The handle b is arranged in line with the three pipes, and is so constructed that both piston-rods are attached to it by means of the connecting-link c c'. The rods c c' are packed airtight in the caps a⁵, so that the pipe a, above 45 its connection with the confluent pipe, and the pipe a', above the discharge a⁶, become air-chambers, into which the air will be more or less compressed in the operation of the pump. The center pipe, a², also is an air-chamber, into 50 which the water will flow and compress the air upward. The piston-rod c extends below

the confluent pipe a³ into the extension a⁴, and is provided with a valve-piston, c³. The lower end of the extension a⁴ rests on the bottom of the well, and the piston c³ is placed so as to be 55 below or very near the surface of the water. If it be arranged to play above the water-level, a check-valve should be placed in the pipe below it, as in the ordinary sucker-pump. A check-valve, d, is placed near the upper end of 60 the extension a⁴ and below the end of the confluent pipe a³.

The valve-piston c³ on the piston-rod c' plays in the lower end of the stand-pipe a' and between the spout a⁶ and the confluent pipe. It 65 is arranged above the level of the lower ends of the three pipes a a' a².

A check-valve, if desired, may be arranged at d'; but its presence is not indispensable, for the pump will operate well without it.

The three pipes may be held in place by any suitable braces—as, for example, the cross-bar e.

The several pipes described hereinbefore may be of any desired length, the relative arrangement of parts being preserved.

The device is specially adapted for deep-well service. A double-lift pump is furnished from which an unintermittent flow of water can be had.

The operation of the device is readily understood. The piston c³ lifts the water into the confluent tube. Considerable quantity of the water will be forced upward into the pipes a a². The water, after it has passed through the confluent tube, is taken by the piston c³ and lifted to the discharge a⁶. If the pump be operated very rapidly, much of the water will be lifted above the discharge a⁶ into the air-chamber in the upper end of the pipe a'. 85

By the construction hereinbefore described it will be seen that I have three air-chambers into which the air will be compressed as the water is drawn upward. This compressed air operates to maintain an unintermittent flow of 90 water.

The central stem, a², contains the main air-chamber, from which the chief benefits of the compressed air are received. The stem serves as a fulcrum for the handle, which is so arranged as to oscillate on its pivotal connection and move the pistons c³ c' in opposite di-

rections at the same instant. When the handle is moved so as to raise piston c^4 the latter acts as a sucker and draws a greater quantity of water through the piston c^3 than would otherwise be brought upward by the said piston c^3 if used alone.

The central pipe, a^2 , could be dispensed with and the handle be pivoted on a suitable framing connected with the pipes a a' . Excellent results would be thus obtained; but I prefer in all cases to have the central air-pipe arranged as shown and described.

Having thus described my invention, what I claim, and desire to secure by Letters Patent, is—

1. In a double-acting sucker or lift pump, the combination of two stand-pipes having air chambers in their upper ends, a confluent pipe uniting the lower ends of the stand-pipes, a supporting-pipe or extension connected to the lower end of one of the stand-pipes, a piston placed in the stand-pipe, from which the water is discharged, and arranged above the end of

the confluent pipe, a piston placed in the supporting-pipe or extension below the end of the confluent pipe, together with the necessary check-valves, piston-rods, and operating mechanisms, substantially as set forth.

2. In a double-acting sucker or lift pump, the combination, with the stand-pipes a a' , having their lower ends united by a confluent pipe, a^3 , of the air-tube a^2 , having its upper end closed and its lower end open and connected to and opening into the confluent tube a^3 at a point between the stand-pipes, and having suitable means on its upper end for holding the lever b for operating the piston-rods and pistons in the stand-pipes, substantially as herein set forth.

In testimony whereof I affix my signature in presence of two witnesses on this 24th day of January, 1881.

WILLIAM S. LANEY.
